UNITED STATES PATENT OFFICE.

DAVID F. WHITEMAN, OF OREGON CITY, OREGON.

TENSION ATTACHMENT FOR WINDING MACHINES.

Application filed August 23, 1923. Serial No. 658,974.

To all whom it may concern:

Be it known that I, DAVID F. WHITEMAN, a citizen of the United States, residing at Oregon City, in the county of Clackamas and State of Oregon, have invented certain new and useful Improvements in Tension Attachments for Winding Machines, of which the following is a specification.

The present invention relates to an improved tension device for winding machines, and has for an object to provide an improved means for varying the tension according to the size of yarn which is being wound.

Another object of the invention is to provide a variable tension device of this character which may be easily and quickly applied to the usual type of winding machines without changing or substituting any of the parts thereof.

Briefly stated, the invention embodies a weight arm which may be hooked upon the usual winding machine in lieu of the ordinary weight and which is held in position upon the machine without the use of brackets, pivots, or the like, and which is permitted to swing or rock upon its fulcrum for exerting the desired pressure on the yarn.

The invention further aims to provide a quick attachment for winding machines wherein a single weight is used and wherein the weight may be quickly adjusted to exert the desired pressure, and wherein the position of the weight may be determined according to the size of yarn or the tension desired.

The above and various other objects of the invention will in part be described in and in part understood from the following detailed description of the present preferred embodiment, the same being illustrated in the accompanying drawing wherein:

Fig. 1 is a fragmentary end elevation of a winding machine having the tension device of this invention applied thereto, and

Fig. 2 is a detail perspective view of the improved tension device.

Referring to the drawing, 10 designates a winding machine of ordinary construction having a spindle 11 on which yarn 12 may be wound, the yarn being taken from a bobbin or spool 13 or other suitable source of supply. The machine carries a tension arm 14 having friction or tension discs 15 between which the yarn 12 is drawn during

the winding operation for securing the necessary tension on the yarn as it is wound upon the spindle 11. The discs 15 are urged together to secure the required tension and an arm 16 bears against one disc and is pivoted upon a horizontal rod 17 carried on the tension arm 14. This pivoted arm 16 is usually constructed of wire the free end of which is looped as at 18 lengthwise of the shaft 17 and has a pivot eye 19 in spaced relation to the arm 16, the pivot eye 19 terminating in a hook 20 adapted to receive the usual weight of desired size. In present practice one of a series of weights must be selected according to the size of the yarn and the tension desired, and hung upon the hook 20.

The present invention provides a weight lever 21 of suitable length provided at one end with a laterally extending fork 22 the arms of which extend upwardly and are spaced apart a distance sufficient to freely receive therebetween the lower edge of the tension arm 14. The fork 22 is merely placed up against the arm 14 so that the lever 21 may rock upon the fork as a fulcrum. The arms of the fork hold the lever 21 from lateral displacement. Spaced a short distance from the fork 22 is an eye 23 formed in the lever 21 for receiving the hook 20 thereto so that the lever is suspended on the hook instead of the usual weight. The outer end of the lever 21 is provided with a row of suitably spaced apart openings 24 adapted to receive a hook 25 of a weight 26. The hook 25 may be engaged in any one of the openings 24, and the openings represent different tensions for the weight upon the hook 20.

The lever 21 may be stamped and bent from sheet metal and the weight may be formed of any suitable material having the necessary specific gravity, such as iron so that the weight may be of a convenient size for handling and will not be bulky or in the way. The weight preferably is of two ounce size because its effective pressure may be varied according to its position upon the lever 21.

The tension device may thus be easily and economically manufactured and may be quickly applied by merely placing the form 22 against the lower edge of the tension arm 14 and fitting the arm 23 over the hook 20. The weight 26 is then suspended upon the

lever 21 so as to exert a downward pull on the hook 20 variable according to the position of the weight 26.

Various changes and modifications may be made in the details of construction and design of the above specifically described embodiment of the invention, the same being restricted only by the scope of the following claims.

10. What is claimed is:

1. A tension device for winding machines having the usual tension arm and weight hook, comprising a lever provided upon one end with an upwardly extending fork for seating against the tension arm and having an eye spaced from the fork to receive said hook therein, said lever having a plurality of openings spaced longitudinally of the lever between the eye and the free end of the lever, and a weight removably positioned in said openings for exerting a variable pressure upon the weight hook.

2. A tension device of the character described comprising a lever having a row of

openings spaced longitudinally of the lever 25 and having a pivot eye inwardly of said openings, said lever having a lateral disposed portion upon its inner end having upwardly extending fork arms and adapted to serve as a fulcrum upon which the lever 30 may swing, and a weight arranged for selective engagement in the first mentioned openings of the lever.

3. A tension device for winding machines comprising a flat bar having a fork bent laterally from its inner end and having its arms extending upwardly for engagement about the tension arm of a winding machine, said bar having an eye spaced from the fork to receive the weight hook of a winding machine and further having a plurality of openings spaced longitudinally of the bar between the first mentioned opening and its outer end, a weight, and a hook on the weight for selective engagement in the last 45 mentioned openings.

DAVID F. WHITEMAN.
